(57) **CLAIM**

The ornamental design for a table leg structure, as shown and described.

DESCRIPTION

FIG. 1 is a first perspective view of a first embodiment of a table leg structure, showing my new design.

FIG. 2 is a front elevation view thereof;

FIG. 3 is a side elevation view thereof;

FIG. 4 is a top plan view thereof;

FIG. 5 is a second perspective view of a second embodiment thereof;

FIG. 6 is a front elevation view thereof;

FIG. 7 is a side elevation view thereof;

FIG. 8 is a top plan view thereof;

FIG. 9 is a third perspective view of a third embodiment thereof;

FIG. 10 is a front elevation view thereof;

FIG. 11 is a side elevation view thereof; and,

FIG. 12 is a top plan view thereof.
